UNITED STATES PATENT OFFICE.

CARL C. SCHMIDT, OF ST. JOHN, NEW BRUNSWICK, CANADA.

DETACHABLE HEEL.

No. 873,388.

Specification of Letters Patent.

Patented Dec. 10, 1907.

Application filed August 15, 1907. Serial No. 388,609.

To all whom it may concern:

Be it known that I, CARL C. SCHMIDT, citizen of Canada, residing at St. John, in the Province of New Brunswick and Dominion of Canada, have invented new and useful Improvements in Detachable Heels, of which the following is a specification.

My invention pertains to elastic or cushion heels for boots and shoes; and it contemplates the provision of a heel of the kind stated embodying simple and light means through the medium of which it may be expeditiously and easily connected to a shoe, and this in such manner that while there is no liability of the heel being casually released while the shoe is in use, yet when necessity demands the heel may be readily detached from the shoe for use upon another shoe or for any other purpose.

Other objects and advantageous features of the invention will be fully understood from the following description and claims when the same are read in connection with the accompanying drawings, forming part 25 of this specification, in which:

Figure 1 is a longitudinal vertical section illustrating the heel constituting the preferred embodiment of my invention as properly attached to the sole of a shoe. Fig. 2 is 30 a transverse section taken in the plane indicated by the line 2—2 of Fig. 1, looking rearward. Fig. 3 is an inverted plan view of the metallic coupler of my novel heel. Fig. 3^a is a plan of the said coupler. Fig. 4 is a perspective view of the cross-bar comprised in the coupler, and Fig. 5 is a detail inverted plan view illustrating a portion of a modified coupler.

Referring by letter to the said drawings, 40 and more particularly to Figs. 1 to 4 thereof: A is a shoe bottom or sole. B is the elastic or cushion pad of my improvement, which is preferably of rubber or some suitable composition containing rubber, and is of the general configuration common to heels—*i. e.*, is tapered at its back and sides toward its under side. C is the frame comprised in the coupler of my novel heel, and D is the cross-bar of said coupler, while E is a screw through the 45 medium of which the said cross-bar is attached to the shoe bottom or sole A.

As shown in Figs. 1 to 3^a, the coupler frame C is of general U-shape with its back

and sides slightly inclined downward and inward to enable it to hold the pad B, and 55 is provided along its upper edge with an inwardly directed flange a. Said frame is also provided at its ends with inwardly directed, upright flanges b, which are of U-shape in plan, Fig. 3^a, and are arranged to afford 60 spaces c between their upper ends and the forward ends of the flange a for a purpose which will be presently pointed out. The cross-bar D of the coupler has its ends d U-shaped to engage the flanges b of the frame 65 C, after the manner illustrated in Figs. 3 and 3^a, and is provided on its upper edge with a forwardly extending apertured lip e through which the screw E extends to fasten the heel to the shoe bottom or sole A. For 70 the sake of lightness and strength both the frame C and cross-bar D of the coupler are preferably formed of sheet-metal which in addition to being resilient, is susceptible of being readily shaped as illustrated. 75

When it is desired to apply my novel heel to a shoe bottom or sole A, the pad B is placed in the coupler frame C, either before or after the cross-bar D is arranged in and engaged with the said frame; the frame C 80 having been engaged with the shoe bottom or sole A precedent to the positioning of the pad B and the cross-bar D in the frame. The frame C is engaged with the shoe bottom or sole A by the arrangement of the flange 85 a above the said bottom or sole A, and hence it will be apparent that when the pad B and cross-bar D are properly placed in the frame, and the cross-bar D is attached to the bottom or sole A through the screw E or any 90 other suitable means, the heel as a whole will be strongly connected to the shoe in such manner that there is no liability of its becoming casually disconnected or loose during the wear of the shoe. When, however, it 95 is desired for any reason to detach the heel from the shoe sole or bottom A, the same may be readily accomplished by removing the screw E, drawing the cross-bar D downward out of engagement with the flanges b 100 of the frame C, and then withdrawing the flange a of the frame C from engagement with the sole A. It will also be apparent that by reason of the flanges b of the frame C, and the flanges d of the cross-bar D 105 being inclined upward and outward as

shown in Fig. 2, the upward movement of the cross-bar D in engagement with the flanges b of the frame C will operate to draw the ends of the said frame C inward, so as to positively engage flange a of the frame C with the shoe sole or bottom A. From this latter it follows that when it is merely desired to merely replace a worn pad B with a fresh pad, the same may be accomplished after the cross-bar D is removed and while the frame C remains in engagement with the sole or bottom A.

The modified construction shown in Fig. 5 is similar to that shown in Figs. 1 to 4, with the exception that the apertured lip e' of the cross-bar D' in Fig. 5; is directed rearward from the said cross-bar. When the said modified construction is employed, the cross-bar D' must obviously be connected to the bottom or sole A precedent to the arrangement of the pad B in the coupler.

It will be appreciated from the foregoing that the metallic coupler of my novel heel may be made quite light, and at small cost, and yet the said coupler is well adapted to withstand for an indefinite period the usage to which detachable cushion heels are ordinarily subjected.

The construction herein shown and described constitutes the best embodiment of my invention known to me, but it is obvious that in the future practice of the invention such changes or modifications may be made as fairly fall within the scope of my invention as defined in the claims appended.

Having described my invention, what I claim and desire to secure by Letters-Patent, is:

1. The combination with an article of foot gear; of a heel comprising a pad, and a coupler holding the pad and made up of a resilient frame which engages the sole of said article, and a forward cross-bar; the said frame and the cross-bar having ends which are interlocked, whereby the cross-bar is enabled to hold the ends of the frame against outward movement.

2. The combination with an article of foot gear; of a heel comprising a pad, and a coupler holding the pad and made up of a U-shaped, resilient frame which engages the upper side of the sole, a cross-bar connected to the ends of the frame and arranged to hold the said ends against outward movement, and a device connecting the said cross-bar to the sole.

3. The combination with an article of foot gear; of a heel comprising a pad, and a coupler holding the pad and made up of a U-shaped resilient frame having an inturned horizontal flange engaging the upper side of the sole, and also having upright inwardly directed flanges, of U-shape in cross-section,

at its ends, and a cross-bar having U-shaped flanges at its ends engaging the said end flanges of the frame, and suitably fixed in position.

4. The combination with an article of foot gear; of a heel comprising a pad, and a coupler holding the pad and made up of a U-shaped resilient frame having an inturned horizontal flange engaging the upper side of the sole, and also having inwardly directed end flanges, of U-shape in cross-section, at its ends, and inclined upward and outward, a cross-bar having similarly inclined end flanges of U-shape in cross-section at its ends engaged with the end flanges of the frame, and also having an apertured lip on its upper edge, and a device extending through the said apertured lip and connecting the cross-bar to the sole.

5. The combination with an article of foot gear; of a heel comprising a pad, and a coupler holding the pad and made up of a resilient frame which engages the sole of said article, a forward cross-bar; said frame and the cross-bar having ends which are interlocked, and a device connecting the said cross-bar to the sole.

6. As a new article of manufacture, a detachable boot or shoe heel comprising an elastic pad, and a metallic coupler holding the pad and made up of a resilient U-shaped frame having an inturned horizontal flange and also having inturned end flanges, and a cross-bar engaged with the end flanges of the frame and arranged to be secured against movement with respect to the frame.

7. As a new article of manufacture, a detachable boot or shoe heel, comprising an elastic pad, and a metallic coupler made up of a frame in which the pad is held and which is arranged to engage the heel portion of a boot or shoe sole, and a cross-bar detachably connected with the ends of the frame and provided with means arranged to be connected to the sole.

8. As a new article of manufacture, a detachable boot or shoe heel comprising an elastic pad, and a metallic coupler made up of a U-shaped, resilient frame in which the pad is held and which is arranged to engage the heel portion of a boot or shoe sole, and a forward cross-bar; the ends of the frame and the ends of the cross-bar being provided with complementary engaged devices arranged on upward movement of the cross-bar to effect inward movement of the ends of the frame.

9. As a new article of manufacture, a detachable boot or shoe heel, comprising an elastic pad, and a metallic coupler made up of a U-shaped, resilient frame in which the pad is held and which is arranged to engage the heel portion of a boot or shoe sole, and a forward cross-bar; the ends of the frame and

the ends of the cross-bar being provided with
complementary engaged devices arranged
on upward movement of the cross-bar to
effect inward movement of the ends of the
frame and the cross-bar being also provided
with means arranged to be connected with
the sole.

In testimony whereof I have hereunto set
my hand in presence of two subscribing wit-
nesses.

CARL C. SCHMIDT.
